UNITED STATES PATENT OFFICE.

JOHN MAXHEIMER, OF NEW YORK, N. Y.

DESIGN FOR BIRD-CAGE.

Specification forming part of Design No. 7,117, dated January 20, 1874; application filed September 2, 1873.
 [Term of Patent 14 years]

To all whom it may concern:

Be it known that I, JOHN MAXHEIMER, of the city, county, and State of New York, have invented a new and original Design for Bird-Cages, of which the following is a specification:

This invention relates to a new design for bird-cages; and consists in forming ornamental rows of beads around the entire cage, one bead at the crossing of the horizontal wire with each filling-wire, and ornamenting each of these beads by attaching to its face an annular plate, through the perforation of which the body of the bead can be seen, thus producing a novel and pleasing effect.

In the accompanying drawing, Figure 1 represents a perspective view of a bird-cage containing my new and original design. Fig. 2 is a detail perspective view, showing the crossings of a horizontal wire with two filling-wires, with the ornamented bead formed at such crossings.

Similar letters of reference indicate corresponding parts in both figures.

A represents a bird-cage of any desired shape and size, and in which *a a* are the horizontal wires, and *b b* the upright filling-wires. At the crossing of each horizontal wire with each filling-wire a bead, B, is formed, so that as many rows of beads may be formed around the cage as there are horizontal wires, as is

clearly shown in Fig. 1. It is evident that the rows of beads must not necessarily correspond with the number of horizontal wires, and that my design is completed if one or more rows of beads are formed around the cage. Such beads B may also be formed on the door of the cage, where the horizontal wires cross the uprights, as shown. Each bead B is ornamented by attaching to its face an annular plate, *c*, as is more fully shown in Fig. 2. The color of the body of the bead can be seen through the perforation of such plate, which, if bead and plate are of different materials, will produce a pleasing effect as to form, as well as to color.

I desire it to be understood that I do not herein claim or confine myself to any manner of attaching the annular plate to the bead, the central projection on the bead herein referred to being one means of attachment for which suitable other appliance may be substituted.

I claim as my invention, and desire to secure by Letters Patent—

The design for the bead B of a bird-cage, said bead being ornamented by the attachment to its face of the annular plate *c*, as shown.

JOHN MAXHEIMER.
